UNITED STATES PATENT OFFICE.

LE ROY W. FAIRCHILD, OF NEW YORK, N. Y.

DESIGN FOR A CIGARETTE-CASE.

SPECIFICATION forming part of Design No. 18,779, dated December 4, 1888.

Application filed November 6, 1888. Serial No. 290,170. Term of patent 3½ years.

To all whom it may concern:

Be it known that I, LE ROY W. FAIRCHILD, of New York, in the county of New York and State of New York, have invented a new Design for Cigarette-Cases, of which the following is a specification.

This invention consists of a design for a cigarette-case.

The accompanying cut or print represents a face view of one side of a box having my design thereon.

The design consists of a heavy mass of scroll-shaped figures covering the entire face of the box, with the exception of a small oblong space 15 at the center, the upper and lower portions of

this central space being filled in with a cluster of flowers, as shown in the cut.

The design as a whole is composed of raised figures struck up so as to impart to it a bold and rich appearance. 20

I claim—

The design herein described and shown for a cigarette-case.

In witness whereof I hereunto set my hand in the presence of two witnesses.

LE ROY W. FAIRCHILD.
